DOOR CHIME

Norman William Stevenson, Macclesfield, England, assignor to V. & E. Friedland Limited, Macclesfield, England, a British company

Filed Mar. 12, 1962, Ser. No. 69,208

Claims priority, application Great Britain Sept. 13, 1961

Term of patent 14 years

(Cl. D72—1)

FIG. 1 is a front perspective view of a door bell showing my new design;

FIG. 2 is a rear perspective view of the door bell shown in FIG. 1, and

FIG. 3 is an enlarged outline view taken on the line 3—3 of FIG. 1.

I claim:

The ornamental design for a door chime, as shown.
